(57) **CLAIM**

The ornamental design for a door pull for sliding doors, as shown and described.

DESCRIPTION

FIG. 1 is a left perspective view of a door pull for sliding doors showing my new design;

FIG. 2 is a right perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a bottom plan view thereof;

FIG. 8 is a top plan view thereof; and,

FIG. 9 is a left perspective view thereof showing the door pull positioned on a door shown in broken lines.

In the drawings, the broken lines represent environmental subject matter and portions of the door pull for sliding doors all of which form no part of the claimed design.
